UNITED STATES PATENT OFFICE

2,494,933

DIAPER

Helen Donahue, Richland, Wash.

Application October 24, 1946, Serial No. 705,448

2 Claims. (Cl. 128—284)

1

The present invention relates to a garment and more particularly to a diaper or the like, such as used for babies and to a novel standard method for folding and tying diaper cloths.

Mothers have many ways of applying diaper cloths to their babies, such as by various folding arrangements. Usually these folds either make the diaper too small for easy pinning on or the folds are so thick that the pins are very difficult to apply through the several folds, and often the safety pins used break open due to the strain of holding several folds of diaper cloth and stick the baby. Accordingly, a general object of the present invention is to provide a novel pinless diaper, whereby the diaper cloth has a standard fold arrangement.

Another object is to provide in a diaper cloth, a novel arrangement and predetermined positioning of the strings or tapes to the cloth, so that the diaper is securely held applied in its standardly folded position and around the waist of the wearer.

With these and other objects in view, the invention consists in the construction and arrangement of the several parts of the garment and the novel method of folding the garment to a standard form, as hereinafter described and particularly pointed out in the claims, it being understood that I do not intend to limit myself to the specific details of construction.

In the drawings:

Figure 1 is a plan view of the diaper cloth spread out showing the several fold lines thereof for forming the same into the garment.

Figure 2 is a view of the cloth folded in half.

Figure 3 shows the same folded in at the sides prior to the next folding step.

Figure 4 shows the cloth folded and the relative position of the tie tapes.

Figure 5 shows a front view of the cloth after it is folded into the finished garment.

Figure 6 is a side view of the garment.

Figure 7 is a perspective view of the garment folded and fastened or tied together.

Referring to the drawing in detail, and first with reference to Figure 1, there is shown a rectangular sheet of material 10 having transverse marginal end portions 11 and 12, and longitudinal marginal side portions 14 and 15. The respective marginal portions are folded over and hemmed and adjacent to respective ends thereof, the respective end of each transverse marginal portion is provided with the tie strings or tapes 16, 17, 18 and 19 respectively.

The respective strings 16 and 17 are secured to the respective corners of the marginal portion 11, and the respective strings 18 and 19 are spaced in a short distance from the respective corners of the marginal portion 12 and secured thereto. Thus, when the sheet 10 is folded over in half end

2

to end, the strings 18 and 19 will be positioned between the strings 16 and 17 (see Fig. 2).

The sheet 10 is provided with a central transverse fold line 21 and intermediate the ends of this fold line is sewed the mid-section of a tape 22, the tie ends 23 and 24 of which are left free. These tie ends are respectively spaced from the adjacent longitudinal edges 14 and 15 a distance equal to the spacing of the tapes 18 and 19 respectively from the edges 14 and 15.

The sheet 10, before being folded in half on line 21, may first be folded in angularly from the said sides of the longitudinal margins on lines 25 and 26 and 27 and 28 to provide for a smooth fit at the crotch portion of the garment, or this may be folded later as shown in Fig. 3. Then it is folded in half on the center line 21 at the tape 22. After this folding step the tie ends or tape ends 23 and 24 are dangling free at the fold on the center line 21 and the tape ends 16, 17, 18 and 19 are at the now opposite marginal ends with the respective ones of the tape ends 18 and 19 substantially opposite to the respective ones of tie ends 23 and 24. Then a baby to be dressed in the garment is positioned on the folded sheet with his or her waist approximately at the marginal ends 11 and 12 and the folded strip is again folded in half upwardly over the baby's stomach (see Fig. 4). Thus, there is provided a double thickness of material at the front and back, that is, a two-ply front panel 30 and a two-ply rear panel 31. With the material so folded the tie strips 23 and 18 and 24 and 19 are adjacent each other at the baby's hips and are then easily tied together to form the waist of the garment. The tape ends 16 and 17 attached to the respective corners of marginal portion 11 now remain untied and are pulled together and tied across the front of the garment (see Fig. 5).

As shown in Figs. 1 and 2, an additional pad 32 may be placed so as to fit between the two plies of rear panel 31. Thus, there is provided an easily applied diaper cloth for babies, having a novelly arranged series of tie tapes and fold lines, for producing a comfortably snug, neat and smooth pinless garment.

While I have specifically described and illustrated my invention for one embodiment only, it is to be understood that the same is not limited thereto, except as defined in the appended claims.

What is claimed is:

1. The method of folding into a garment a rectangular single ply sheet of diaper cloth having tie strings at each end and a centrally secured transversely disposed tie tape providing two tie strings midway between the ends of the sheet, comprising the steps of folding the material on a transverse line along the line of said tie tape to provide a substantially square two ply body, fold-

ing in each corner of the square at the secured ends of the tape strings whereby to give to the body a short edge and an opposite parallel long edge, folding the body in half between said edges to form two-ply front and rear panels, tying the said panels together with the tie tape strings and certain of the end tie strings to form a waist portion, then lapping the corners of the rear panel over the front panel, and then tying said corners together with the remaining end tie strings.

2. A diaper garment of the character stated comprising a relatively long rectangular sheet of material, a pair of tie strings secured to a face of the sheet on a line running transversely thereof, midway between the ends of the sheet, each string being spaced a substantial distance inwardly of a side edge of the sheet, a pair of tie strings secured at one end edge of the sheet, each

5 at a corner thereof, and a pair of tie strings secured to the other end edge of the sheet and each spaced inwardly from a side edge of the sheet a distance approximately equal to the spacing of each string of said pair from a side edge of the sheet.

HELEN DONAHUE.
